US0D1105064S

(12) **United States Design Patent** (10) **Patent No.:** **US D1,105,064 S**
(45) **Date of Patent:** **** Dec. 9, 2025**

(54) **COORDINATE INPUT DEVICE**

(71) Applicant: **Wacom Co., Ltd.**, Kazo (JP)

(72) Inventor: **Naoya Nishizawa**, Tokyo (JP)

(73) Assignee: **Wacom Co., Ltd.**, Kazo (JP)

(**) Term: **15 Years**

(21) Appl. No.: **29/923,175**

(22) Filed: **Dec. 28, 2023**

(30) **Foreign Application Priority Data**

Jun. 30, 2023 (JP) ..... 2023-013534 D

(51) **LOC (15) Cl.** **14-02**

(52) **U.S. Cl.**

USPC **D14/341**

(58) **Field of Classification Search**

USPC D14/138, 314, 345, 346, 356, 371

CPC G06F 1/16; G06F 1/1601; G06F 1/1615;

..... G06F 1/1616; G06F 1/1618; G06F

..... 1/1624; G06F 1/1633

(57) **CLAIM**

The ornamental design for a coordinate input device, as shown and described.

DESCRIPTION

FIG. 1 is a front-left-top perspective view of a coordinate input device according to my new design;

FIG. 2 is a rear-right-bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The dashed broken lines in the drawings show portions of the coordinate input device that form no part of the claimed design.

1 Claim, 6 Drawing Sheets
